UNITED STATES PATENT OFFICE.

EUGENE J. SHARADIN, OF LOS ANGELES, CALIFORNIA.

COMBINED SCRAPING AND FINISHING PLANE.

Application filed April 22, 1924. Serial No. 708,134.

To all whom it may concern:

Be it known that I, EUGENE J. SHARADIN, a citizen of the United States, and a resident of Los Angeles, in the county of Los Angeles and State of California, have invented certain new and useful Improvements in Combined Scraping and Finishing Planes, of which the following is a specification.

My invention relates to and has for its purpose the provision of a plane which, in addition to being simple, inexpensive and durable in construction, provides means by which relatively wide blades of various widths can be effectively used in one and the same plane to permit the plane to be used either as a scraping or finishing plane for flooring, furniture or interior trim.

It is also a purpose of my invention to provide a combined scraping and finishing plane having simple and effective means for adjusting the blade to produce the desired cut, and rigidly holding the blade in any adjusted position irrespective of its width.

My invention also provides a handle bar associated with the body of the plane to permit concentration of pressure on the plane and in such manner as to prevent wavering of the plane during movement over the work, thereby insuring a straight course and even planing.

I will describe only one form of combined scraping and finishing plane embodying my invention, and will point out the novel features thereof in claims.

35 In the accompanying drawing—

Figure 1 is a view showing in top plan one form of combined scraping and finishing plane embodying my invention.

Figure 2 is a vertical longitudinal sectional view taken on the line 2—2 of Figure 1.

Figure 3 is an enlarged detail perspective view of the wedge block and depending extension embodied in the plane shown in the preceding views.

Referring specifically to the drawings, in which similar reference characters refer to similar parts, my invention in its present embodiment comprises a frame including blocks 15 and 16, preferably formed of wood, and side plates 17 secured to the edges of the blocks by screws or other suitable fastening member, and in such manner that the confronting ends of the blocks are rigidly supported in spaced relation to provide therebetween a slot 18 through which a

blade 19 is adapted to extend. As clearly shown in Figure 2, the under sides of the blocks 15 and 16 are recessed at points indicated at 15^a and 16^a, respectively, so that when the blade 19 is in proper position within the slot 18 the cutting edge 19^a of the blade 19 will be disposed within the opening provided by the recesses 15^a and 16^a. The rear edge of the front block 15 is recessed to accommodate a pressure strip 20 formed of wood or other suitable material and having a pressure edge 20^a against which the blade 19 is adapted to bear and to be rigidly held, as will be more fully described hereinafter.

On top of the blocks 15 and 16, adjacent their meeting edges, are secured bars 21 and 22 which are shaped at their confronting sides to form, in effect, a continuation of the wedge shaped slot 18. These bars are secured to the blocks and to the side plates 17, and bracing strips 23 are secured to the blocks at the outer sides of the bars to provide further means for securing the bars in fixed position upon the blocks. Upon the bar 21 is secured a handle bar 24, such bar extending transversely of the plane body and having handle grips 25 disposed at opposite sides of the plane and adapted to be gripped when manipulating the plane, as will be understood. At the rear side of the bars 21 and 24 a stabilizing plate 26 formed of metal or other suitable material is arranged and, as clearly shown in Figure 2 the lower edge of this plate engages the upper edge of the pressure strip 20. This plate is held in the position shown in Figure 2 by means of manually operable screws 27, 28 and 29, the plate being tapped to threadedly receive the screws so that when the latter are in applied position the plate will be securely held in contiguous relation to the bars 21 and 24. The screws 27 and 28, as shown in Figure 2, extend downwardly through the bar 21 and the plate 26 for engagement with the blade 19, while the screw 29, which is arranged above the screws 27 and 28, is disposed substantially in a horizontal plane for engagement with the blade 19 at a point above the screws 27 and 28. The several screws are provided with flat heads to permit the manual manipulation thereof, and as these screws function to firmly lock the blade 19 in adjusted position they are termed clamping or locking screws.

For the purpose of adjusting the blade 19 to any desired angle within the slot 18, the bar 22 is provided with three screws 30, 31 and 32, these screws threadedly engaging the 5 bar and having their inner ends disposed within the slot 18 for engagement with the rear side of the blade 19. The screws 30 and 31 are disposed in the same horizontal plane, and are provided with slotted heads to permit 10 their manipulation by means of a screwdriver, while the screw 32 is provided with a flat head to permit manipulation thereof and this screw is arranged above and between the screws 30 and 31 for engagement 15 with the blade 19 at a point between and above the screws 30 and 31.

The invention as illustrated in the drawing is shown as including a wedge block 33 having a depending extension 34, this block 20 being interposed between the stabilizing plate 26 and the blade 19 and having the extension 34 disposed in the path of movement of the screw 29 so as to be engaged by the inner end thereof when the screw is in active 25 position. The use of this wedge block 33 is not necessary to the successful clamping or locking of the blade 19 in adjusted position and, therefore, may be dispensed with. However, in order to positively insure 30 the locking of the blade in adjusted position and to eliminate the necessity of the adjustment of the screw 29 to cause its inner end to actually engage the blade 19, the block may be employed and the extension 34 35 providing a surface against which the screw 29 bears.

In practice, a blade designed for the preliminary scraping of a surface, and which blade is preferably about three inches in width, is inserted in the slot 18, the adjustment 40 of the screws 30, 31 and 32 determining the angle which the blade is adapted to assume. The blade can be movably clamped by an adjustment of the screws 27, 28 and 29 which will co-operate with the screws 30, 31 and 32 in holding the blade so as to prevent it dropping from the slot, but yet allowing 45 manual adjustment of the blade so that the proper set of the cutting edge can be secured. After the blade has been properly adjusted it can be locked in adjusted position by further adjustment of the screws 27, 28 and 29, such adjustment forcing the blade firmly against the screws 30, 31 and 32 50 and firmly holding the blade against the pressure edge 20^a of the strip 20. The plane is now ready for use, and with the narrow scraper blade imperfections in the surface of a piece of wood can be removed and the surface made fairly level. To finish the surface 55 the narrow blade is removed and a wider blade, say five or six inches in width, is substituted. By employing a blade of this width all marks made by the narrow blade can be removed from the surface of 60

the work and the surface made perfectly level and thoroughly smooth so that by using emery or garnet paper a perfectly finished surface is produced.

It is to be particularly noted that because 70 of the arrangement of the adjusting and locking screws the blade, either with or without the block 33, can be securely held in firm contact with the pressure edge of the strip 20 so that when operating the plane the blade cannot lose its adjustment or its cutting edge bend and thus form imperfections in the surface of a piece of work. Further, the arrangement of the handle bar 75 transversely and centrally of the plane body allows concentration of pressure on the plane and in such manner as to prevent wavering thereof during movement so as to insure a straight course and even planing.

Although I have herein shown and described only one form of combined scraping and finishing tool embodying my invention, it is to be understood that various changes and modifications may be made herein without departing from the spirit of the invention and the spirit and scope of the appended claims.

What I claim is:

1. A combined scraping and finishing plane comprising a frame including blocks, side plates securing the blocks in spaced relation to provide a slot between the blocks, a pressure strip secured to one of the blocks within said slot, supporting bars on the blocks at opposite sides of the slot, bracing strips secured to the blocks and abutting the bars, screws adjustable in one of the bars determining the lateral adjustment of a blade within the slot, a stabilizing plate on the inner side of the other bar, screws adjustable in the last mentioned bar and plate for engagement with the blade to firmly secure the latter in adjusted position against said pressure strip, and a handle bar extending transversely of the plane and secured to one of said bars.

2. A combined scraping and finishing plane comprising a pair of blocks, side plates securing the blocks in spaced relation to provide a slot between the blocks, a pressure strip secured to one of the blocks within said slot, supporting bars on the blocks at opposite sides of the slot, a stabilizing plate associated with one of the bars, locking screws engaging the plate and the corresponding bar, and adjusting screws movable in the other bar.

3. A combined scraping and finishing plane as embodied in claim 2, wherein the locking and adjusting screws each comprise a pair of screws disposed in one plane and a third screw above and between the first screws.

4. A combined scraping and finishing plane comprising a frame having a slot

therein, bars secured to the frame at opposite sides of the slot, a stabilizing plate associated with one of the bars, adjusting screws carried by the other bar, and locking screws 5 extending through the first bar and said plate, a wedge block adapted to be inserted between the plate and a blade disposed within the slot, and an extension on the block adapted to be engaged by one of the 10 locking screws.

5. A combined scraping and finishing plane as embodied in claim 4, wherein the locking and adjusting screws each comprise a pair of screws disposed in one plane and a 15 third screw above and between the first screws.

6. A combined scraping and finishing plane comprising a frame including blocks spaced to provide a slot, a pressure strip 20 secured to one of the blocks within the slot, means for determining the angle of a blade adapted to be disposed in the slot, and means co-operating with the first means for securing the blade in adjusted position and 25 for urging the latter into engagement with said pressure strip.

7. A combined scraping and finishing plane comprising a frame having a slot 30 therein, a pressure strip secured to the frame within said slot, supporting bars on

the frame at opposite sides of the slot, bracing strips secured to the frame and abutting the bars, adjustable means in one of the bars for determining the lateral adjustment of a blade within the slot, a stabilizing plate on the other bar, and adjustable locking means in the last mentioned bar and plate for engagement with the blade to firmly secure the latter in adjusted position 35 against said pressure strip.

8. A combined scraping and finishing plane comprising a frame having a blade-receiving slot therein, a pressure strip within the slot, bars on the frame at opposite sides of the slot, adjusting screws carried by one of the bars, locking screws carried by the other bar, and a plate associated with the last bar and in which said locking screws are threaded.

9. A combined scraping and finishing plane comprising a frame having a slot 40 therein, a pressure member secured to the frame, means for determining the angle of a blade adapted to be disposed in the slot, and means co-operating with the first 45 means for securing the blade in adjusted position and for urging the blade into engagement with the pressure member.

EUGENE J. SHARADIN.
